UNITED STATES PATENT OFFICE.

WADE W. BOWMAN, OF YONKERS, NEW YORK, ASSIGNOR TO CONTINUOUS CLOTH TOWEL CABINET CO., INC., OF NEW YORK, A CORPORATION OF NEW YORK.

BEARING.

1,415,142.

Specification of Letters Patent.

Patented May 9, 1922.

Original application filed February 15, 1917, Serial No. 148,714. Divided and this application filed July 21, 1921. Serial No. 486,465.

To all whom it may concern:

Be it known that I, WADE W. BOWMAN, residing at Yonkers, county of Westchester, State of New York, have invented certain new and useful Improvements in Bearings, of which the following is a specification.

This invention relates to an improved bearing, the same being a division of pending application Serial No. 148,714, towel holder, filed February 15, 1917.

The object of this invention is to provide a bearing which may be cheaply and easily manufactured and which will at the same time be highly efficient for its purpose.

Other objects and aims of the invention, more or less specific than those referred to above, will be in part obvious and in part pointed out in the course of the following description of the elements, combinations, arrangements of parts and application of principles, constituting the invention, and the scope of protection contemplated will be indicated in the appended claims.

In the accompanying drawings, which are to be taken as a part of this specification, and in which I have shown merely a preferred form of embodiment of the invention:

Figure 1 is a transverse sectional view through a bearing constructed in accordance with this invention.

Figure 2 is an elevational view of the bearing seen in Fig. 1, and

Figure 3 is a sectional view taken upon the plane of line III of Fig. 1.

Referring to the drawings for describing in detail the structure which is illustrated therein, the reference character L indicates a wall member upon which it is desired to pivotally support a roller or the like, as G. The roller has a spindle H projecting from the end thereof by which to support the roller. The wall L is formed with an opening 1 therethrough which the spindle projects.

Within the opening 1 is positioned a thimble 2. One end of this thimble is flanged over, as at 3, to engage one surface of the wall L adjacent the opening 1, and the opposite end of the thimble is flanged over, as at 4, to engage the outer surface of a saucer-like brace member 5.

The member 5 has its marginal portions 6 resting against the surface of the wall

L opposite to the flange 3 and a central opening 7 through which the thimble projects.

The member 5 inversely serves to support the outer end of the thimble so that the thimble is correctly held to receive the spindle H.

If desired a separately formed collar 8 may be positioned about the thimble and between the outer surface of the wall L and the inner surface of the member 5, between the flanges 3 and 4 so that pressure applied for suitably bending down said flanges will be properly resisted without necessity for the employment of otherwise unnecessarily heavy material for the part 70 5. A bearing thus constructed may be of any desired length, and this is particularly valuable in instances where the wall L upon which the spindle, as G, must find its support, is itself too thin to constitute an efficient bearing. Where the wall, or like supporting member, as L, is of sheet metal, for instance, the opening, as 1, therethrough would provide a spindle bearing surface which would soon cut into the spindle. A bearing of such proportions would also wear away rapidly and would not retain lubricant. With the sleeve or thimble 2 present, however, said thimble or sleeve may be made in any proportion to provide the desired extent of bearing surface.

While such a bearing is particularly adapted for the mounting of rollers, such as are illustrated in the original application, nevertheless it will be apparent that they are equally adaptable for the mounting of spindles and shafts in various other devices and mechanisms. Here it may be noted that an essential characteristic of the device is that it serves to provide a lengthened bearing, or supporting aperture, as compared with the thickness of the piece of metal to which it is attached. It is obvious, therefore, that it may, if desired, serve merely as an efficient means for the attachment or support of parts. If a shaft, or other element, for instance, is to be attached to a plate, or sheet of material, which plate or sheet is itself too thin to provide a proper attaching or supporting part, a bearing constructed in accordance with this invention may readily be employed to afford proper support or attach-

ing means. Accordingly, the term "bearing" as herein used, is not intended to be limited to a device for the support or accommodation of a rotating shaft. On the contrary, the relative size of parts may be such that, if desired, the sleeve of this bearing shall grip tightly upon the shaft, or other element, so that any movement of the one shall be communicated directly to the other. All of the parts entering into the construction of this bearing are of simple form easily made and cheap to produce especially in quantities.

Also the parts are such as can be readily and cheaply assembled with uniform accuracy.

Also, only the part which serves as the bearing proper; namely, the sleeve, or thimble, 2, need be of relatively costly bearing metal.

As many changes could be made in this construction without departing from the scope of the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A bearing comprising a supporting member, a saucer-shaped member having its open end resting against one surface of the supporting member, and a sleeve extending thru mating apertures in the saucer-shaped member and in the supporting member, the end portions of the sleeve being flanged over upon the adjacent portions of the saucer-shaped member and the support to retain all of said parts in fixed relation.

2. A bearing comprising a supporting member, a saucer-shaped member having its open end resting against one surface of the supporting member, a sleeve extending thru mating apertures in the saucer-shaped member and in the supporting member, the end portions of the sleeve being flanged over upon the adjacent portions of the saucer-shaped member and the support to retain all of said parts in fixed relation, and a collar surrounding the sleeve to sustain pressure from the flanged over portions of the sleeve.

3. A bearing comprising a supporting

member, a saucer-shaped member having its open end resting against one surface of the supporting member, a sleeve extending thru mating apertures in the saucer-shaped member and in the supporting member, the end portions of the sleeve being flanged over upon the adjacent portions of the saucer-shaped member and the support to retain all of said parts in fixed relation, and a member interposed between the supporting member and a portion of the saucer-shaped member to sustain pressure from the flanged over portions of the sleeve.

4. A bearing comprising a supporting member having an aperture therethru a sleeve extending thru said aperture having one of its ends flanged outwardly to engage the supporting member and having its other end extending beyond the supporting member, and means engaging between the supporting member and said second end of the sleeve serving to hold the sleeve in bearing position.

5. A bearing comprising a supporting member having an aperture therethru, a sleeve extending thru said aperture having one of its ends flanged outwardly to engage the supporting member and having its other end extending beyond the supporting member, a member extending from the supporting member outwardly to adjacent the second end of the sleeve, and said second end of the sleeve being flanged over upon said member to retain all of said parts in fixed relation.

6. A bearing comprising a supporting member having an aperture therethru, a sleeve extending thru said aperture having one of its ends flanged outwardly over one surface of the supporting member and having its other end extending beyond the opposite surface of the supporting member, and a collar surrounding said sleeve being clamped between the second surface of said supporting member and a part of the second end portion of the sleeve whereby to retain all said parts in fixed relation.

In testimony whereof I affix my signature in the presence of two witnesses,

WADE W. BOWMAN.
